AUTOMATIC RECLOSED CIRCUIT
BREAKER SYSTEM

E. Vernon Ellett, Pocahontas, Va., assignor to
Westinghouse Electric & Manufacturing Com-
pany, East Pittsburgh, Pa., a corporation of
Pennsylvania

Application March 11, 1933, Serial No. 660,377

17 Claims. (Cl. 175—294)

My invention relates, generally, to circuit breaker systems, and, more particularly, to automatic reclosing circuit breaker systems.

Heretofore, it has been the usual practise to effect automatic reclosing operations of a circuit breaker by means of a device or systems which provided only for a predetermined number of timed reclosures. I have discovered that in many instances operating conditions are such that timed reclosures are not always desirable and especially is this true as regards the first reclosure. In an ever increasing number of applications of automatic reclosing equipment the need for a substantially instantaneous first reclosure is appearing. The meaning of a substantially instantaneous reclosure as referred to herein, is that the reclosure is effected without imposing a time delay other than the necessary short time required for the relays and circuit breaker mechanism to function.

The periodic reclosing systems of the prior art are not adapted for service of this kind since they are so designed as to impose a time delay on the first as well as the other reclosures and are entirely inadequate to fulfill the present day needs.

The object of my invention, generally stated, is to provide an automatic reclosing circuit breaker system which shall be simple and effective in operation and which may be economically manufactured and installed.

A more specific object of my invention is to provide for automatically effecting a plurality of reclosing operations of a circuit breaker in a predetermined manner and sequence.

A further object of my invention is to provide for automatically reclosing a circuit breaker in such manner that the first reclosure is effected substantially instantaneously followed by a plurality of timed reclosures.

Another object of my invention is to provide for automatically reclosing a circuit breaker, a predetermined number of times, the first reclosure being effected immediately upon the opening of the breaker, the remaining reclosures being effected at predetermined timed intervals and the reclosing system rendered ineffective in the event that the breaker reopens following the last reclosure.

These and other objects of my invention will become evident from a reading of the following description taken in conjunction with the drawings, wherein:

Figure 1 is a diagrammatic view of an automatic reclosing circuit breaker system embody-

ing the principal features of the invention wherein alternating current is used for control purposes, and;

Fig. 2 is a diagrammatic view of a similar system adapted for direct current control.

In practising my invention in both instances the first reclosure is effected substantially instantaneously in response to the automatic opening operation of the breaker.

A predetermined number of subsequent reclosures are effected by means of a timing relay in the event that the breaker continues to be automatically tripped following the first reclosure. The operation of the timing relay is initiated upon the first automatic opening of the breaker.

The systems are so arranged that in the event the breaker remains closed after any reclosure except the last one the timing relay is automatically returned to its original or normal position. In the event that the breaker fails to remain closed on the last reclosure, such as would be the case if a fault condition still existed in the circuit controlled by the breaker, provision is made for rendering the reclosing system inoperative to prevent further reclosures.

Referring now to the drawings and to Fig. 1 in particular, the reference character 10 designates generally, a circuit breaker which may be connected, in a well known manner, between a power supply circuit 11 and a load circuit 12.

The circuit breaker 10 is provided with a closing device in the form of a solenoid 13 and a tripping device 14. The tripping device 14 has been shown as a simple, spring-biased latching device which functions to hold the breaker in the closed position and which may be operated to automatically trip the breaker in response to an overload on the load circuit by means of the current transformer 9, as shown, or in accordance with any other desired abnormal condition of the circuit.

Any other well known type of closing device may be used as the reclosing system herein described is suitable for application to all forms of circuit breakers.

In this embodiment of the invention the control current for the various devices may be obtained from a suitable transformer 8 connected to the supply circuit 11, as shown.

The energization of the closing solenoid 13 may be controlled by a control relay 15. This relay may be operated by means of a push-button switch 16 when manual control of the breaker is desired such as to initially close the breaker.

In addition to the control relay 15, there is

provided a cut-off relay 17 which functions to release the control relay and thereby deenergize the closing solenoid 13 following each reclosure of the breaker.

5 In order to effect a substantially instantaneous reclosure of the breaker following the initial automatic opening thereof, a set-up relay 18 is utilized, which, in this instance, is controlled by means of a suitable back contact or limit 10 switch 19 on the breaker.

10 In order to provide for automatically effecting a timed reclosure or a plurality of timed reclosures following the instantaneous reclosure of the breaker in the event that it reopens, a timing 15 relay 21 is utilized. For convenience the timing relay is illustrated as a motor-operated drum device, although it is to be understood that any other suitable timing device may be used instead.

15 As shown, the timing relay 21 comprises a drum element disposed to be driven by means of a suitable alternating current motor 22 and provided with a plurality of stationary contact fingers 23 to 28, inclusive, a continuous ring segment 29 and a plurality of separate segments 30 to 33, inclusive and 40. The ring segment 29 functions in connection with fingers 23, 24 and 25 to control the operation of the relay motor 22, as will be described more fully hereinafter.

20 In order to render certain elements of the reclosing systems ineffective after each reclosure whereby any further attempt to reclose will be precluded in the event that the control voltage should collapse when the breaker is closed, there is provided a lock-out device 34 in the form of a 25 toggle relay, which cooperates with and is controlled by relay 18 in controlling the operation of the control relay 15 and is further controlled by the timing relay 21 to reset the system for operation after each lockout in a manner which will be more clearly described hereinafter.

25 In order that a more comprehensive understanding of the nature and objects of my invention may be obtained, a detailed description of the operation will now be given.

30 Assuming that the switch 35 is closed, thereby energizing the control conductors X and Y, the circuit breaker 10 may be initially operated to its closed position by closing the push-button switch 16 which establishes an energizing circuit for the control relay 15 which extends from conductor Y through the switch 16, winding of relay 15, contact members 36 of the cut-off relay 17 and conductor 37 to conductor X. In response to the operation of the control relay 15 the closing solenoid 13 is energized to effect the closing of the breaker over a circuit which extends from conductor Y through contact members 38 of relay 15, conductor 39 and coil of solenoid 13, to control conductor X.

35 In order to provide for effecting a substantially instantaneous first reclosure of the breaker, the set up relay 18 is rendered initially responsive to the closure of a limit switch or back contact member 19 on the breaker. The closure of this limit switch 19 establishes an energizing circuit for the set-up relay 18 which extends from conductor Y through conductor 41, contact members 26 and 27 bridged by the segment 30 on the timing relay 21, conductor 42, contact members 43 of the lockout relay 34, conductors 44 and 53, winding of relay 18, limit switch 19 and conductor 45 to control conductor X. As will be observed the energization and operation of the set-up relay 18 at this time depends upon the lockout relay 34

and the timing relay 21 being in their normal or non-operating positions.

40 In response to the operation of the set-up relay 18, the lockout relay 34 is operated over a circuit which extends from control conductor X through contact members 46 of the set up relay 18, conductor 47 and winding 48 of the lockout relay to the control conductor Y. This operates the lockout relay 34 to the lockout position thereby closing its contact members 49 which establishes an energizing circuit for the control relay 15. This circuit extends from the energized conductor 42 through conductor 51, contact members 52 of the set-up relay 18, conductor 53, contact members 49, conductor 54, winding of relay 15, contact members 36 of the cut-off relay 17 and conductor 37 to the control conductor X. The control relay 15 is thereupon operated to energize the closing solenoid 13 as described hereinbefore, to effect a substantially instantaneous first re- 20 closure of the breaker.

45 The set-up relay 18 is maintained in its closed position until the breaker is closed, even though the contact members 43 of lockout relay 34 are opened to interrupt its original energizing circuit by means of contact members 52 which are connected in shunt relation to contact members 43. Upon the closure of the breaker, the limit switch 19 is opened and the set-up relay 18 is de- 30 energized.

50 In order to provide for reclosing the breaker, a predetermined number of times at predetermined time intervals following the first reclosure in the event that the breaker continues to reopen, provision is made for initiating the operation of the timing relay 21 in response to the initial automatic opening of the breaker.

55 In this instance the energizing circuit for operating the relay motor 22 is completed by means of a second limit switch 55 on the breaker. This circuit extends from conductor Y through conductor 41, contact members 23 and 24 bridged by the continuous segment 29, conductor 56, limit switch 55, conductor 57, and the armature of the motor 22 to conductor X. 45

60 The time delay relay 21 is continued in operation, regardless of the fact that the limit switch 55 is opened as soon as the breaker is reclosed, by means of contact members 58 on the lockout relay 34 which are closed to short circuit the limit 50 switch 55 before the breaker is reclosed.

65 In order to provide for deenergizing the control relay 15 and consequently the solenoid 13 after the breaker has been closed, the cut-off relay 17 is energized upon the closure of the breaker by means of a third limit switch 61 which establishes an energizing circuit from conductor X through conductor 45, limit switch 61, conductor 62, winding of relay 17, conductor 63 and contact members 64 of the control relay 15 to conductor Y. The 60 operation of relay 17 opens its contact members 36 to deenergize the control relay 15 which opens its contact members 64 to deenergize relay 17.

70 In the event that the breaker reopens following the first reclosure, it is prevented from reclosing immediately since the set-up relay 18 is no longer responsive to the opening operation of the breaker as its energizing circuit is now interrupted at contact members 43 of the lockout relay 34, thereby requiring that the lockout relay 34 be reset or 70 returned to its initial position. In this instance the resetting of the relay 34 is controlled following each opening of the breaker by means of the contact segments 31 and 33 on the timing relay 21.

75 As will be observed, when the drum of the tim- 75

ing relay 21 is actuated such that contact fingers 27 and 28 are bridged by the segment 31 a circuit is established from conductor Y through conductor 41, contact fingers 27 and 28, bridged by segment 31, conductor 66 and the reset coil 67 of lockout relay 34 to conductor 37. The lockout relay is thereupon actuated to its normal or initial position where its contact members 43 are again closed.

- 10 It will be observed, however, that the energizing circuit for the set-up relay 18 is still incomplete since the contact fingers 26 and 27 of the timing relay 21 are now disengaged from the segment 30. After the expiration of a predetermined time interval as determined by the speed of the timing relay or spacing of contact segments 30 and 31 on the drum, contact segment 32 which corresponds to contact segment 30 is actuated into engagement with contact fingers 26 and 27 which completes 20 the energizing circuit for the set-up relay 18 which, in turn, operates the lockout relay 34 to effect the operation of the control relay 15, as described hereinbefore, to reclose the breaker a second time.
- 25 In the event that the circuit breaker opens a third time, the timing relay 21 continues to function and bridges contact fingers 27 and 28 by means of the segment 33 to reset the lockout relay 34 and then bridges contact members 26 and 30 27 by means of segment 40 to effect a reclosure of the breaker as described hereinbefore.

As illustrated, the timing relay 21 is provided with only two reset segments 31 and 33, and, therefore, should the breaker open a fourth time, the absence of any additional re-set segments will prevent the lockout relay 34 from being operated to its reset position, which effects a definite lockout of the system. The energizing circuit for the relay motor 22 of the timing relay is maintained 40 through contact members 58 of the lockout relay and it continues to operate until the contact finger 23 is disengaged from the segment 29, which interrupts the motor energizing circuit and stops the timing relay in such position that its 45 contact fingers 26 and 27 are not bridged by the contact segment 30 thereby making it impossible for the set-up relay 18 to operate in response to the opening of the breaker even though the lockout relay 34 should in some manner be returned to 50 its reset position.

The complete reclosing system is rendered temporarily inoperative and cannot again function automatically until the breaker is closed manually by means of the push-button switch 16 as described hereinbefore.

In order to reset the timing relay 21 and thereby render the reclosing system effective for further automatic operation, the timing relay 21 is provided with a contact finger 25 which is so disposed as to be engaged by the segment 29 when the drum is stopped in the lockout position. When the breaker is closed manually a fourth limit switch 68 is closed which establishes a circuit from conductor Y through conductor 41, contact fingers 24 and 25 bridged by the segment 29, conductor 69, limit switch 68, conductor 57 and armature of the motor 22 to conductor X. The completion of this circuit starts the timing relay 21 and the drum is actuated until the contact finger 25 is disengaged from the segment 29 which interrupts the previously traced energizing circuit for the motor 22. The timing relay is now in its normal non-operating position as shown.

In the event that the circuit breaker remains 75 closed in response to any reclosure, the timing

relay 21 is automatically returned to its normal non-operating position by means of the energizing circuit described in the preceding paragraph.

It will be apparent that any number of reclosing operations at any desired time intervals may be obtained by providing the required number of segments on the drum of the timing relay. These segments may be placed at regular intervals as shown in order to obtain an equal time element between each reclosure or may be so spaced as to obtain reclosures at different time intervals.

It is to be understood that even though the system of Fig. 1 is particularly adapted for use where alternating current control is desired or necessary, it may be used to equal advantage for 15 direct current control.

Referring now to Fig. 2, there is illustrated a reclosing system having the same general characteristics as the system of Fig. 1 but being adapted for use in connection with direct current control, 20 although this system may also be used for alternating current control when desired.

In this instance the timing relay 71 is generally similar to that shown in Fig. 1 with the exception that there is a different arrangement of contact 25 fingers and segments. In this instance the relay is provided with stationary contact fingers 72 to 78, inclusive. The fingers 72, 73 and 74 are disposed to cooperate with a continuous ring segment 79 to control the operation of the motor 81 30 which drives the drum, contact fingers 75 and 76 are disposed to cooperate with the segments 82, 35 83 and 84 to control the operation of the set up relay 18 after the first reclosure, and contact fingers 77 and 78 are disposed to cooperate with segments 85, 86 and 87 to control the operation of the control relay 88.

In this embodiment of the invention, the control relay 88 is provided with a latching device 89 adapted, when energized, to disconnect the armature 91 from the contact members 92 for a purpose which will be described hereinafter.

In this instance the control relay 88 may be operated to initially close the breaker by means of a push-button switch 93 which operates the control relay 88 to establish an obvious energizing circuit for the solenoid 13.

In response to the first opening of the breaker the limit switch 19 is closed to establish an obvious energizing circuit for the set up relay 18. In response to the operation of relay 18, its contact members 94 are closed to complete an energizing circuit for the control relay 88 which extends from positive battery through contact members 94, conductor 95, contact fingers 77 and 78 of the timing 55 relay which are bridged by the segment 85, conductor 96 and winding of relay 88 to negative battery. This effects the operation of the control relay 88 to again energize the closing solenoid 13 to effect a substantially instantaneous reclosure of 60 the breaker.

In response to the operation of the set-up relay 18, its contact members 97 are closed to complete an energizing circuit for the relay motor 81 which extends from positive battery through contact 65 fingers 72 and 73 bridged by the segment 79, conductor 98, contact members 97 and the armature and field winding of motor 81 to the negative battery.

In order to render the set-up relay 18 ineffective 70 to prevent a second reclosure of the breaker the releasing mechanism 89 of the control relay 88 is rendered responsive to the closure of the breaker by means of limit switch 95 which closes in response to the breaker being operated to its fully 75

closed position to effect the energization of the releasing device. This permits the contact members 92 of the control relay to drop thereupon de-energizing the closing solenoid 13, and, at the same time, the armature 91 is disconnected from these contact members, thereby making it impossible for the set up relay 18 to reclose the breaker before contact fingers 77 and 78 have been disengaged by the contact segment 85.

- 10 In the event that the breaker has reopened immediately the set up relay 18 is operated as before. It is apparent, however, that the armature 91 of the control relay 88 is not released until the contact segment 85 disengages the contact fingers 77 and 78. When this occurs the armature 91 drops and is engaged by the latch 89 thereby rendering it in condition for a second operation.

When the set up relay 18 was closed, it was maintained in the closed position by means of a holding circuit which extends from positive battery through its contact members 99, conductor 101, contact fingers 75 and 76 bridged by the segment 82, conductor 102 and through the coil of relay 18 to negative battery. As will be readily understood, this circuit maintains the set up relay in its closed position until the segment 82 has disengaged from contact fingers 75 and 76 which provides sufficient time to close the circuit breaker.

- 15 The timing relay 71 continues to operate until at the expiration of a predetermined time interval contact fingers 77 and 78 are bridged by the segment 86 which, if the breaker has reopened to operate the set up relay 18, completes the previously described energizing circuit for the control relay 88. In this instance the holding circuit for the set up relay 18 is established by the contact segment 83 on the drum element.

In the event that the breaker opens a third time, it is again reclosed when the contact segment 87 engages the contact fingers 77 and 78 in the same manner as described hereinbefore.

- 20 In the event that the breaker should open a fourth time, it is prevented from being reclosed since the contact finger 72 now becomes disengaged from a continuous segment 79 and the timing relay 71 stopped in its lockout position.

As described in connection with Fig. 1, the reclosing system may be again rendered operative by manually closing the breaker by operating the push-button switch 93 which, in this instance, effects the closure of limit switch 68 to complete an energizing circuit for the relay motor 81 which extends from positive battery through contact fingers 73 and 74 bridged by the continuous segment 79, conductor 104, limit switch 68, conductor 103 and the armature of motor 81 to negative battery. As soon, however, as contact finger 74 disengages segment 79 the motor 81 will be deenergized to stop the timing relay in its initial or normal non-operating position.

25 In the event that the breaker remains closed at any time prior to the lockout position of the timing relay, this relay will be returned to its normal position through the functioning of the circuit described in the preceding paragraph.

It may be stated in conclusion that while the illustrated example constitutes a practical embodiment of my invention, I do not wish to limit myself strictly to the exact details herein illustrated, since modifications of the same may be made without departing from the spirit of the invention as defined in the appended claims.

I claim as my invention:

1. In an automatic reclosing circuit breaker system, in combination, a circuit breaker, means

for opening the circuit breaker, and means including a set-up relay, a timing relay and a lockout relay alternately responsive to said relays responsive to the opening operation of the breaker for effecting a substantially instantaneous reclosure thereof, said means being disposed to effect a predetermined number of additional reclosures of the breaker in the event that it continues to reopen following the first reclosure.

2. In an automatic reclosing circuit breaker system, in combination, a circuit breaker, means for opening the circuit breaker, means including a lockout relay and a control relay responsive thereto responsive to the opening of the circuit breaker for effecting a substantially instantaneous first reclosure thereof, and means including said means operable to effect a predetermined number of additional timed reclosures in the event that the circuit breaker reopens subsequent to the first reclosure thereof.

3. In combination a power supply circuit and a load circuit, a circuit interrupter for controlling the flow of current between said circuits, means for automatically opening the interrupter in response to predetermined circuit conditions, means for closing the interrupter, control means responsive to the opening operation of the interrupter for effecting a substantially instantaneous operation of the closing means, said control means including lockout means having normal and lockout positions operable to the lockout position to render the control means ineffective in the event that the breaker reopens immediately, and means also responsive to the opening of the interrupter for operating the lockout means to the normal position whereby the control means is again rendered effective to close the interrupter at the expiration of a predetermined time interval.

4. In combination a power supply circuit and a load circuit, a circuit interrupter for controlling the flow of current between said circuits, means for automatically opening the interrupter in response to predetermined circuit conditions, means for closing the interrupter, control means responsive to the opening operation of the interrupter for effecting a substantially instantaneous operation of the closing means, said control means including lockout means operable to render the control means ineffective, and a timing device initiated into operation in response to the opening of the breaker for operating the lockout means to a different position and cooperating therewith to operate the control means to reclose the interrupter after a predetermined interval of time.

5. In an automatic reclosing circuit interrupter system, in combination, a circuit breaker provided with closing means and automatic tripping means, a control relay for controlling the energization of the closing means, a set-up relay operable in response to an opening operation of the interrupter, lockout means controlled by the set-up relay for effecting the operation of the control relay whereby the interrupter is reclosed substantially instantaneously, said lockout means being disposed to render the set-up relay unresponsive to a subsequent opening of the interrupter, and a timing relay responsive to the initial opening operation of the interrupter for again operating the lockout means to render the set-up relay responsive to the opening of the interrupter after a predetermined time interval following the first reclosure and for again ren-

dering the lockout means operative in response to the operation of the set-up relay, whereby the second and subsequent reclosures of the interrupter may be effected at predetermined time intervals.

6. In combination, a circuit interrupter, means for automatically opening the interrupter under predetermined conditions, and means comprising a set-up relay and a lockout relay for automatically reclosing the interrupter substantially instantaneously on the first reclosure and thereafter at predetermined time intervals, said means also including timing means set into operation in response to the initial opening of the interrupter and effective to operate the lockout and set-up relays in a timed sequence following each reclosure to control the timed reclosures and to preclude further reclosures beyond the predetermined number.

7. In combination, a circuit interrupter, means automatically operable to open the interrupter under predetermined conditions, means for closing the interrupter, and means including a set-up relay operable in response to the opening of the breaker and a control relay responsive to the means including the set-up relay for controlling the closing means to effect a predetermined number of reclosures of the interrupter, said means being adapted to effect a substantially instantaneous first reclosure of the interrupter followed by a predetermined number of timed reclosures and to become inoperative in the event that the interrupter opens on the last reclosure.

8. In combination with a power supply circuit, a load circuit and a circuit interrupter therebetween, of means for automatically opening the interrupter in response to predetermined abnormal conditions of the load circuit, means set into operation in response to the opening of the interrupter for thereafter controlling the reclosing thereof, said means including a control relay and switch means responsive to the opening of the breaker disposed to effect a substantially instantaneous first reclosure and timing means disposed to co-operate with said switch means to operate the control relay at predetermined intervals to effect a predetermined number of timed reclosures in the event that the abnormal conditions persist, said timing means being automatically operable to reset to an initial position in the event that the interrupter remains closed upon any reclosure thereof.

9. In an automatic reclosing circuit breaker system, in combination, a circuit breaker provided with means for tripping the breaker in response to predetermined circuit conditions, means for closing the breaker, a timing relay, a lock-out relay, and a set-up relay, said set-up relay being responsive to the opening of the breaker for operating the lock-out relay to a predetermined position to effect the energization of the breaker closing means, and to render the set-up relay unresponsive to a reopening of the breaker, said timing relay being responsive to the initial opening of the breaker and operable through a sequence whereby the lock-out relay is operated to a different predetermined position at the expiration of a predetermined time interval and the set-up relay operated at the expiration of a second predetermined time interval to again operate the lock-out relay to said first predetermined position to reclose the breaker.

10. In an automatic reclosing circuit breaker system, in combination, a circuit breaker, means

for automatically opening the breaker, means for closing the breaker, a timing relay operable through a predetermined sequence in response to the opening of the breaker, a lock-out relay operable to a plurality of positions, and a set-up relay responsive to the opening of the breaker for operating the lockout relay to a predetermined position to cause the closing means to effect a substantially instantaneous reclosure of the breaker and to render said set-up relay unresponsive to the reopening of the breaker, said timing relay being disposed to operate the lockout relay to its initial position at the expiration of a predetermined time interval and to operate the set-up relay at the expiration of a second predetermined time interval whereby the lockout relay is again operated to its said predetermined position to reclose the breaker, said timing relay being further operable to effect a predetermined number of additional timed reclosures in the event that the breaker continues to reopen.

11. In an automatic reclosing circuit breaker system, in combination, a circuit breaker, means for automatically opening the breaker, a timing device, and control means including a control relay and a set-up relay initially responsive to the opening of the breaker for effecting a substantially instantaneous reclosure thereof and for initiating the operation of the timing device, said timing device being operable thereafter in co-operation with the set-up relay to effect a predetermined number of operations of the control relay at predetermined time intervals whereby a predetermined number of timed reclosures are effected in the event the breaker continues to re-open.

12. In an automatic reclosing circuit breaker system, in combination, a circuit breaker, means for automatically opening the breaker, a timing relay operable through a predetermined sequence and having a normally non-operating position, a control relay operable to close the breaker, a set-up relay responsive to the opening of the breaker for effecting the operation of the control relay to effect a substantially instantaneous reclosure of the breaker and for initiating the operation of the timing relay, means responsive to the closure of the breaker for rendering the control relay unresponsive to the set-up relay in the event that the breaker reopens immediately to close the breaker, said timing relay being operable to thereafter render the control relay responsive to the set-up relay for a predetermined number of times at predetermined intervals to effect a predetermined number of timed reclosures of the breaker in the event it continues to reopen.

13. In an automatic circuit breaker system, in combination, a circuit breaker provided with closing means, means for opening the breaker automatically in response to predetermined conditions, a control relay for controlling the energization of the closing means, a lock-out relay having a normal reset position and a lockout position and operable to the lockout position to effect the operation of the control relay and a set-up relay responsive to the opening of the breaker when the lockout relay is in the reset position for actuating the lockout relay to the lockout position, thereby to reclose the breaker substantially instantaneously.

14. In an automatic reclosing circuit breaker system, in combination, a circuit breaker, means for automatically opening the breaker in response to predetermined conditions, means including a lockout relay operable in response to

- the initial opening of the breaker to effect a substantially instantaneous reclosure thereof, said lockout relay being operated from a reset position to a lockout position to render the means including the lockout relay unresponsive to an immediate opening of the breaker, and a timing relay responsive to the opening of the breaker for alternately operating the lockout relay to the reset position and rendering the means including the lock-out relay responsive to the open condition of the breaker for a predetermined number of times at predetermined intervals.
15. In an automatic reclosing circuit breaker system, in combination, a circuit breaker, means for opening the breaker under predetermined conditions, closing means for the breaker, a timing relay having contact elements which are closed in a predetermined sequence, relay means responsive to the opening of the breaker and disposed to co-operate with the timing relay to reclose the breaker substantially instantaneously and to become unresponsive to an immediate re-opening of the breaker, and means responsive to the opening of the breaker for initiating the operation of the timing relay, said timing relay being operable to render the relay means responsive to the open condition of the breaker for a predetermined number of times at predetermined intervals.
30. 16. In an automatic reclosing circuit breaker system, in combination, a circuit breaker, means for automatically opening the breaker, closing means for the breaker, a control relay for controlling the energization of the closing means, means responsive to the closure of the breaker for rendering the control relay ineffective to energize the closing means, a timing relay, a set-up relay responsive to opening operations of the breaker for energizing the control relay and to initiate the operation of the timing relay, said timing relay being disposed to thereafter render the control relay responsive to the set-up relay for a predetermined number of times at predetermined time intervals in the event that the breaker continues to reopen.
17. In an automatic reclosing circuit breaker system, in combination, a circuit breaker provided with closing means, means for automatically opening the breaker, a time-delay relay having a non-operating position operable to a plurality of control positions, control means responsive to the opening of the breaker for energizing the closing means substantially instantaneously and for initiating the time-delay relay into operation, said time-delay relay being disposed when in its non-operating position to co-operate with the control means in reclosing the breaker in response to the initial opening thereof and to thereafter render the control means responsive to the open condition of the breaker at predetermined intervals, thereby to provide a substantially instantaneous first reclosure followed by timed reclosures in the event the breaker continues to open.

E. VERNON ELLETT.
